UNITED STATES PATENT OFFICE.

ADOLPH E. HERMAN, OF RAVENNA, OHIO.

SPRING-VEHICLE.

SPECIFICATION forming part of Letters Patent No. 288,634, dated November 20, 1883.

Application filed July 30, 1883. (No model.)

To all whom it may concern:

Be it known that I, ADOLPH E. HERMAN, a citizen of Ravenna, in the county of Portage and State of Ohio, have invented a new 5 and useful Improvement in Spring-Vehicles, of which the following is a specification.

The principal object of my invention is to dispense with a reach and equalize the vertical movement of the box in all its parts, and 10 prevent tilting when the weight or downward pressure is applied at any part of the box.

In the drawings forming a part of this specification, Figure 1 is a side elevation, and Fig. 2 is a view of the bottom, of the vehicle.

15 The front end of box *b* is attached to fifth-wheel *w*, and the rear end is connected by rods *l* with block *v* on spring *d*. Spring *d* turns with the front axle, *x*, in clip *a*. The location of fifth-wheel *w* may be changed, if preferred, 20 by placing it between axle *x* and spring *d*, and in that case the spring will not turn with the axle.

25 Rod *s* is hinged to clip *a* at one end and to link *s'* at the other end. Link *s'* is hinged to lug *s''*, attached to the bottom of box *b*. Rod *n* is hinged to link *s'* at one end, and to a crank or wrist, *n'*, on rod *g*. Rod *g* has an oscillating movement, and is supported by staples *n''* in the bottom of box *b*. Rod *a'* is hinged at 30 one end to crank or wrist *n'* and at the other to rod *e*. The upper end of rod *e* is hinged to lug *e'*, at the bottom of box *b*, and its lower end is hinged to one end of rod *i*. The other end of rod *i* is hinged to the rear axle, *x'*. Rod *g* extends across or nearly across the bottom of 35 box *b*, and is formed with short cranks *c c* at its ends, to which rods *c c* are hinged. The other ends of rods *c c* are hinged to the rear axle, *x'*.

40 The rods hereinabove described are relatively so arranged that all of them are moved and springs *d d'* are compressed whenever a sufficient weight or downward pressure is brought to bear on any part of box *b*. To illustrate, if the whole weight be on the front end of box *b*, it forces down and back rods *s, n*, and *a'*, turning crank *n'* back and cranks *c c* for-

ward, and forcing back and down rods *e* and *i* and the hind part of box *b*. The relative positions of the various parts will then be as indicated by dotted lines in Fig. 2. The same result will follow if the weight be on the hind end of the vehicle. Rods *e* and *i* will then be forced down and back, rods *a'* and *n* will be drawn back, thus forcing down rod *s*, link *s'*, and the forward end of box *b*. If the weight be all on either side of box *b*, the box will not tilt, but both sides of it will be forced down to substantially an equal extent. This effect is produced through rod *g* in this way: When 60 either side of box *b* is pressed down, the inclined rod *e'* on that side will turn forward cranks *c c*, at both sides of box *b*, and also turn backward crank or wrist *n'*, thereby drawing back rods *n, a', e*, and *i*, and forcing down rod 65 *s* and the box. Rods *s, n, a', e*, and *i* are arranged centrally of the bottom of box *b*, between axles *x x'*, in order to have an equal effect on both sides of the box.

In a two-wheeled vehicle rods *n s* and link 70 *s'* may be dispensed with. As cross-rod *g* and rods *c c* are mainly to prevent lateral tilting of the box, they may be removed, and a single hinged rod-connecting link, *s'*, with rod *e'*, may be used in place of the two rods *n* and *a'* for 75 the purpose of bracing the axles and equalizing the compression of the two springs.

I claim as my invention—

1. The hinged rods *i e a' c'* and the cross-rod *g*, having cranks *c c n'*, in combination with axle 80 *x'*, spring *d'*, and box *b*, substantially as described.

2. The box, axles, and springs of a vehicle, in combination with the hinged rods *i e*, connected by one or more hinged rods with link 85 *s'* and rod *s*, substantially as described.

3. A vehicle-box, axles, and springs, in combination with hinged rods *s n a' e i c' c'*, cross-rod *g*, having cranks *c c n*, and link *s'*, substantially as described.

ADOLPH E. HERMAN.
